WASTE RECEPTACLE

Phillip L. Brookshire, Cincinnati, Ohio, assignor to The
Witt Company, Cincinnati, Ohio, a corporation of Ohio

Filed June 14, 1965, Ser. No. 85,724

Term of patent 14 years

(Cl. D58—17)

First

FIGURE 1 is a perspective view of a waste receptacle embodying my new design.

FIGURE 2 is a front elevational view.

FIGURE 3 is a side elevational view.

FIGURE 4 is a top plan view.

FIGURE 5 is a bottom plan view thereof, on a reduced scale.

The characteristic feature of my design resides in the provision on a waste receptacle of the general design shown of a wide raised band extending over the top and the two substantially vertical sides of the cover all as shown.

I claim:

The ornamental design for a waste receptacle, substantially as shown and described.
